CLAIM

The ornamental design for a tablet stand, as shown and described.

DESCRIPTION

FIG. 1 is a front, right side, top perspective view of a tablet stand showing my new design;

FIG. 2 is a rear, left side, bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a front, right side, top plan view thereof showing the tablet stand in a partially collapsed state; and,

FIG. 10 is a front, right side, top plan view thereof showing the tablet stand in a fully collapsed state.

The broken lines depict portions of the tablet stand that form no part of the claimed design.

1 Claim, 10 Drawing Sheets
